CLAIM

The ornamental design for an extruder insert, as shown and described.

DESCRIPTION

FIG. 1 is a perspective view of an extruder insert showing my new design;

FIG. 2 is a back view of an extruder insert showing my new design;

FIG. 3 is a top view of an extruder insert showing my new design;

FIG. 4 is an end view of an extruder insert showing my new design;

FIG. 5 is a front view of an extruder insert showing my new design;

FIG. 6 is a bottom view of an extruder insert showing my new design; and,

FIG. 7 is a cross-sectional view taken along line 7—7 of FIG. 2.

The broken line showing of a cylinder grouping is included for the purpose of illustrating non-claimed subject matter and forms no part of the claimed design.
